COMBINED PACKAGING AND STORAGE TRAY FOR SHAVING ACCESSORIES

Ernst Reichl, Birkenweg, Germany, assignor to The Gillette Company, Boston, Mass., a corporation of Delaware

Filed Mar. 13, 1968, Ser. No. 10,947

Term of patent 14 years

Int. Cl. D9—04

U.S. Cl. D9—242

Fig. 1

Fig. 2

FIG. 1 is a perspective view taken from one corner of a combined packaging and storage tray for shaving accessories showing my new design; and

FIG. 2 is a perspective view thereof taken from the diagonally opposite corner.

The bottom of the design is substantially plain and unornamented.

I claim:

The ornamental design for a combined packaging and storage tray for shaving accessories, as shown and described.
